Attorney.

UNITED STATES PATENT OFFICE.

HENRY A. NAYLOR, OF BOSTON, MASSACHUSETTS.

FASTENING FOR SHOES, LEGGINGS, GLOVES, AND THE LIKE.

1,202,090.

Specification of Letters Patent. Patented Oct. 24, 1916.

Application filed May 2, 1916. Serial No. 94,983.

To all whom it may concern:

Be it known that I, HENRY A. NAYLOR, a subject of Great Britain, and now resident of Boston, county of Suffolk, and State of 5 Massachusetts, have invented an Improvement in Fastenings for Shoes, Leggings, Gloves, and the like, of which the following description, in connection with the accompanying drawings, is a specification, like 10 letters on the drawings representing like parts.

My present invention is an improved fastening for shoes, leggings, gaiters, gloves, and similar wearing apparel where a strong, 15 durable, and at the same time, yielding and flexible fastening is desired.

My improved device is specially applicable to boots and shoes, and it is an object of the invention to provide a pair of co- 20 operating metallic fastening members which will have means to prevent catching or tearing the apparel of the wearer, and yet which will be maintained constantly in engagement during the flexing and movement of the shoe 25 and wearer's foot therein.

It is a still further object of the invention to provide coöperating metallic hook members which may be readily attached or detached from each other and which will re- 30 main in hooked engagement through a normally acting yielding tension or "spring" directly from the attaching means which retains the coöperating hook members on to the opposite sides of the shoe lacing openings. 35 This spring feature is of value and importance because the two coöperating members will remain in hooked engagement during a considerable range of movement of the shoe parts and because the foot of the wearer 40 is entirely relieved from undue strain or inconvenience from the metallic members, said members being preferably entirely supported by the attaching means, such as eyelets.

In carrying out my invention I may either 45 form the hook attaching members integral with a suitable attaching device such as the shoe eyelet and flange which is ordinarily employed in securing lacing studs to boots and shoes. This has the further advantage 50 of enabling my improved fastening to be set by the present hook setting machines in general use.

Further details of the invention and advantages will be hereinafter further pointed out and claimed.

Referring to the drawings, illustrating

preferred embodiments of the invention, Figure 1 is a plan view of a pair of metallic fastening members secured to a fragmentary portion of a boot or shoe upper adjacent the lacing opening; Fig. 2 is a cross sectional view on the line 2-2 of Fig. 1; Fig. 3 is a modified form showing the hook and eyelet member in undeturned position; Figs. 4 and 5 are plan and cross sectional views respectively of a slightly modified form, Fig. 5 being on the line 5-5 of Fig. 4.

While I have herein illustrated my novel fastening devices as applied to a boot and shoe, it will, of course, be understood that 70 I am not so limited, but that it is within the scope of the invention to utilize this novel type of fastening for similar uses, such as wearing apparel of many kinds, gloves, rain-coats, gaiters, corsets, and the like.

Referring to the drawings, a fragmentary portion of the opposite sides of a boot and shoe upper is indicated at 1 and 2 and the lacing tongue 3, to which upper portions are attached the coöperating fastening devices 80 comprising a hook member 4 and its attaching eyelet 5 securing the same to the portion 1 of the shoe upper, and an eye member 6 with its attaching eyelet portion 7 secured to the upper portion 2. Preferably each eye- 85 let portion 5 and 7 has the usual retaining flange 8 and "upsetting" or clenching flange 9, so that the fastening devices may be secured to the upper by any of the well-known eyelet or lacing hook setting machines now 90 in use. The hook member 4 I prefer to form of substantially elongated or oval shape, having a hook 10 at its forward portion with a rounded end adapted to fit upon and engage the corresponding eye portion, as 95 shown at 11. Both the hook 10 and eye engaging portion 11 are preferably so formed to coöperate with each other and substantially fill the hook opening and thus prevent the catching of any wearing apparel thereon. I 100 also prefer to form these members 4 and 6 with openings therethrough, as indicated at 12 and 13, so that each member will be light, strong, and of attractive appearance and may be ornamented, nickelized, lacquered, or otherwise finished to match the wearing apparel with which they are used. Cross bars 14, 14, on the members 4 and 6 are provided which are adapted to coöperate with a bearing or spring member 15 on each eyelet flange, as clearly indicated in Fig. 2. This 110 affords a strengthening, reinforcing, and

spring tension member for the top fastening devices 4 and 6, holding the hook part 10 and coöperating eye 11 free of the tongue 3 and hence of the foot and acting as a fulcrum 5 or spring bearing over which the fastening members 4 and 6 may be pressed to hold the hook and eye ends under yielding tension. This feature is of special importance as I find that it enables the flexing of either 10 side of the upper throughout a considerable range of movement to be freely made without disengaging the hook and eye portions of my fastening device. Thus the shoe and foot may yield under the movements incident 15 to walking, running or jumping without disengaging the fastening device and yet permitting full freedom of movement of the wearer. In Fig. 3 I have illustrated a similar pair of attaching devices, only with the 20 hook 20 "underturned" instead of upturned as in Figs. 1 and 2. This construction is feasible, since the bearing members 15 hold the hook well above the tongue and hence above the foot and prevent the same from 25 rubbing against the wearer. This construction is especially advantageous as a non-catching hook on boots and shoes for ladies' wear.

In Figs. 4 and 5 I have illustrated a modification wherein the eyelet member 21 of usual type is used to secure the fastening members 22 and 23, which fastening members may be of the hook and eye type illustrated in Figs. 1 and 2 and as shown in Figs. 35 4 and 5, or of the underturned hook type illustrated in Fig. 3. In the form of fastening device shown in Figs. 4 and 5 I prefer to make the fastening devices independently 40 of the attaching eyelet, forming each member with a bottom portion 24 adapted to encircle the barrel of the eyelet 21 to be engaged by the flange 25 of the eyelet, which flange is of greater diameter than the opening in the portion 24. The forward member 45 of each bottom portion 24 is upturned as shown in Fig. 5 at 26 to constitute a bearing for the cross bar of the fastening members, in a similar manner to that already described in connection with the preceding figures.

50 The fastening devices of my invention are further capable of economical manufacture, being readily stamped out from sheet material and bent into suitable shape while cold. The bearing members 15 or 26, while preferably formed on the eyelet setting or bottom portion of the device, may, of course,

be formed directly on the crossbar of the fastening members and project downwardly, bearing upon the setting flange of the eyelet, or, as in the modification shown in Figs. 4 60 and 5, on the bottom part 24. However, I prefer to form these bearing members substantially as shown in the drawings and consider that making same integrally with the top members is a mere reversal of parts and 65 therefore within the scope of the appended claim.

It will be appreciated that my novel form of fastening devices eliminates entirely the necessity for shoe lacing, cords or the like; 70 the fastening devices are complete when attached to the shoe or other articles, completing the fastening device without other expense or labor. Furthermore, my fastening device does not wear out as a lacing 75 does, and is therefore permanent, usually outlasting the article to which it is attached, and eliminating the objections of the old style lacing cords which are constantly 80 wearing out, fraying, etc.

It will be appreciated that my fastening device, while described as being made, preferably, of a metallic material, may be formed of any suitable wear-resisting substance having sufficient tensile strength and 85 ductility to be employed for the purpose described. I have in mind particularly the adaptability of such materials as celluloid, bone, vulcanized rubber, or the like. In such modified forms it will be appreciated that 90 the fastening device is firm, strong, and substantially indestructible, as distinguished from the prior lacing cords, which quickly 95 frayed out.

My invention is further described and defined in the form of a claim as follows:

As an article of manufacture, metallic hook and eye fastener members, each member comprising a fastener part coöperating with the other member, means to secure the 100 same to stock, and a projecting combined spring and guard, formed integrally with said member to constitute a metallic support for the fastener part, being rigidly supported adjacent said securing means.

In testimony whereof, I have signed my name to this specification, in the presence of two subscribing witnesses.

HENRY A. NAYLOR.
